UNITED STATES PATENT OFFICE.

ANDREW SEATON, OF OSBORN, MISSOURI, ASSIGNOR OF ONE-HALF TO
LELLO E. KELLEY, OF OSBORN, MISSOURI.

DEVICE FOR OPERATING MAIL-BOX LIDS.

No. 817,591.

Specification of Letters Patent.

Patented April 10, 1906.

Application filed June 22, 1905. Serial No. 266,468.

To all whom it may concern:

Be it known that I, ANDREW SEATON, a citizen of the United States, residing at Osborn, in the county of Dekalb and State of Missouri, have invented certain new and useful Improvements in Devices for Operating Mail-Box Lids, of which the following is a specification.

This invention relates to mail-boxes, and 10 pertains especially to a device for operating the lids of rural mail-boxes.

The object of the invention is to provide a novel and peculiar device attached to the hinged lid of a rural mail-box for opening the 15 box.

A further object of the invention is to provide a device for opening rural mail-boxes whereby the lid of the box may be raised for the purpose of collection and delivery within 20 the mail-carrier or postman alighting from the mail-wagon.

A still further object of the invention is to provide a device for raising the lid of mail-boxes and holding the same open for the handling 25 of mail-matter without the mail-carrier alighting from the mail-wagon and to make such connection between the device and the lid that the latter will close simultaneously with passage of the wagon from the box.

With these objects in view the invention 30 consists in the peculiar arrangement of levers relative to the mail-box and in the manner of connecting the levers to the box-lid to open it.

The invention further consists in a pair of 35 levers one of which is pivoted to a mail-box post and the other of which is attached to the box-lid and a link connecting the said pair of levers together to open the box.

In the accompanying drawings, forming 40 part of this application, Figure 1 is a perspective view showing the application of the invention. Fig. 2 is an elevation looking at the end of the box with the latter open. Fig. 3 45 is a perspective view of the lid-lever, partly broken away.

The same reference-numerals denote the same parts throughout the several views of the drawings.

For purposes of exemplification the invention 50 will be shown and described in connection with a rectangular mail-box and a square post; but it is quite as applicable to boxes and

posts of various shape or character having a hinged lid.

The post 1 may be of special design or an ordinary fence-post may be employed. The mail-box 2 is attached to the post in the usual manner and has a hinged lid 3. The device for operating the lid comprises a lever 4, pivotally hung from the post and under the box by eyes 5 and having a long arm 6, projecting from the post a distance sufficient to be engaged by the wheels or body of a mail-wagon, and a short arm 7, projecting from under the box beyond one of its ends, a lever 8 extending over the top of the box and curving back of the latter and having diverging ends forming hooks 9, adapted to fit the front rim of the lid, and a link 10, pivoted to and connecting the lid-lever and the short arm of the post-lever.

It is obvious that a mail-wagon has simply to be driven against the long arm of the post-lever, which will carry the latter to one side 75 and raise the lid. The wagon is stopped in front of the box to hold the lid raised, so that the carrier may deposit or collect mail from the box without holding the lid open and without alighting from the vehicle. Then 80 the passage of the vehicle from the box will permit the long lever to swing back to closed-lid position.

It will be seen that the hook affords means for detachably connecting the lid-lever to the 85 lid, so that in the event of injury to the lid or change of boxes the levers are not changed.

Having thus described my invention, what I claim as new, and desire to secure by Letters Patent, is—

1. The combination, with a mail-box having a swinging lid, of means for operating the lid, comprising a pair of levers one of which is pivoted to swing horizontally and the other of which is connected to the lid to swing vertically, and a link connecting the levers.

2. The combination, with a mail-box having a swinging lid, of a lever pivoted to swing horizontally and having arms projecting therefrom, a vertically -swinging lever attached to the lid and connected to one arm to open and close the lid according to the movement of the other arm.

3. The combination, with a mail-box, of a swinging lid, of a lever pivoted to swing perpendicular to the movement of the lid, a le-

ver attached to the lid, and a link connecting said levers.

4. The combination, with a mail-box having a hinged lid, of a lever pivoted to swing horizontally and having long and short arms projecting therefrom at different angles, a lever attached to the lid, and a link connecting the lid-lever and the said short arm.
5. The combination, with a mail-box having a hinged lid, of a lever extending over the lid and having diverging arms terminating in

hooks adapted to grasp the lid-flange, a lever pivoted to swing at right angles to the movement of the lid, and a link connecting said levers.

In testimony whereof I affix my signature in presence of two witnesses.

ANDREW SEATON.
